BENAIAH FITTS, OF NEWARK, NEW JERSEY.

Letters Patent No. 72,619, dated December 24, 1867.

IMPROVEMENT IN PLANING-MACHINES.

The Schedule referred to in these Letters Patent and making part of the same.

TO ALL WHOM IT MAY CONCERN:

Be it known that I, BENAIAH FITTS, of Newark, county of Essex, State of New Jersey, have invented a new and useful Improvement in Cylinder Planing-Machines; and I do hereby declare that the following is a full, clear, and exact description of the construction and operation of the same, reference being had to the annexed drawings, making a part of this specification, in which—

Figure 1 is an elevation, and

Figure 2 is a plan of the machine—

The same letters referring to the same parts in all.

The invention relates to certain improvements in that class of machines in which planing surfaces of boards, (commonly called surfacing,) and pointing or matching, sometimes called tongue and grooving, are all done with one machine, and consists mainly in the arrangement of the different parts, so as to perform the greatest amount of work with the greatest convenience, it being so constructed that it may be changed from a broad-surfacer to a single or double jointer, or a matcher and surfacer.

The construction is as follows: *a* is a framework supporting the other parts of the machine; *b b b* are the feed-rolls, by which the boards are fed through the machine; *c* is the cutter-cylinder, that planes the surface of the boards; *d, e, f*, and *g*, are cutter-cylinders, that joint or match the edges; they are made to rotate upon vertical shafts, on the lower end of which are pulleys *i i i i*, for the belts that drive them; *d* and *g* rotate in stationary boxes; *e* and *f* rotate in movable boxes; *j j* are screws, that hold in place, or slide back and forth, as desired, the boxes with cutter-cylinder *e f*; *h* is a cross-bar, to which the boxes holding cutter-cylinder *d e f g* are attached in such a manner that they can be made to slide across the machine for the purpose of jointing or matching different widths of boards; *l* is the driving-shaft, to which power is applied, and in which are pulleys that drive the different parts of the machine; *k k* are gears on feed-rolls; *m* is a gear connecting the two parts of feed-rolls together, and is driven by gear *n*; *o* is a pulley made fast to gear *n*, and is driven by a belt from the driving-shaft *l*, and thus drives the feed-rolls; *p* is a cone-pulley on driving-shaft for driving feed-pulley *o*; it is so constructed, that by moving it along on the shaft the belt will run on the different sizes, and thus the feed-rolls may be made to run any speed desired; *r s* is a shipper or binder, carrying a roll or pulley *q*, resting on feed-belt *t*, and used for two purposes, one to stop and start the feed, the other to secure the same tension on the belt *t*. Where different sizes of the cone *p*, are used, the arms *r* and *s* are connected together by the segment *v*, which is held in place by thumb-screw *x*, and may be lengthened or shortened at pleasure. The arm or handle *b* is held in position by a catch on the side of the frame. Shown at *w w w w* are half-twist belts, that drive the matched cylinders. *A A* are the belts that drive the surfacing-cylinder; *B B* the boards being planed and jointed. *E E* are recesses on places formed on the frame *a* to receive the cylinders *e* and *f*, when the machine is used as a broad-surfacer. If it is desired to use the machine as a single-jointer or matcher, as would be the case with wide boards, either *e* or *f* may be drawn to one side, using only one part of the vertical cutters.

The operation is as follows: Machines built for surfacing are usually required to plane twenty-four inches wide, but that class of lumber that is usually jointed or matched, is seldom over six inches. In the machines as now constructed, the feed-belt and cone-pulley occupy much of the space occupied in this by the belts *w w w w*; so that jointing or matching is done on one side of the machine only, and when it is desired to use the machine as a surfacer, the jointer or matching-cylinder, with its vertical shafts and pulleys, has to be removed entire from the machine, except in some modern improved machines, the matching-cylinders are set in a frame, and may be dropped down out of the way; but in either, when it is required to use them again, much time is consumed in replacing them, as accuracy in the height of the cutter is necessary to give an even surface. Boards that are cut out roughly to be jointed or matched, usually vary in width, and have to be assorted, and all that will work one width (say six inches) are laid in one pile, and all that will work another width, (say five inches,) in another. The machine is then set for one width, and that is planed and jointed; then it is set for the other, and that is planed.

It will be seen by the above-described construction of this machine, two boards may be planed and jointed or matched at one time, thus doing double the work. The cutter-cylinders *d* and *e* may be set for one width, and *f* and *g* for another, and thus save the labor of assorting the boards before commencing to plane.

It will be seen; too, that it may be changed into a broad-surfacer by simply throwing off the belts *w w w w* and running the cutter-cylinders *e f* out into the recess *E E*, and, as the height has not been altered, they may be replaced by simply running them back again.

One of the features of this machine is in the construction of the cone-pulley *p*, in connection with shipper *r s*, it being so constructed that different speeds may be had, while once the width of the belt in space only is occupied, thus admitting of its being placed upon one side, entirely out of the way. The characteristic feature is forming recesses *E E* in frame *a*, and extending the slide *h* far enough beyond lines drawn from the ends of cylinder *c* perpendicular to its axis, to admit of the vertical or matching-cylinders *e* and *f* being carried off out of the way of the boards, when the machine is used for a broad-surfacer.

Thus having set forth my invention, what I claim as new, and desire to secure by Letters Patent, is—

Forming recesses *E E* in frame *a*, and extending the slide *h* far enough, and for the purpose of transferring the vertical cylinders *e* and *f* beyond lines drawn from the ends of cylinder *c* perpendicular to its axis, substantially as shown and described.

BENAIAH FITTS.
